ASHTRAY

Anthony A. Holler, Lansing, Ohio

Application January 4, 1938, Serial No. 183,360

1 Claim. (Cl. 131—240)

This invention relates to ashtrays, and more particularly to an improved ashtray simulating the gripping of the cigarette between the fingers, and which is so constructed that condensation with the resultant smudge between the cigarette and the supporting means is eliminated and which is also so constructed that the cigarette will burn evenly until it is burnt to a stub.

Another object of this invention is to provide a structure which will support the cigarette in a position out of contact with the tray or material within the tray, and which also supports the cigarette in a manner whereby the burning end of the cigarette will not contact with the support and the cigarette will not thus burn unevenly so that when it is picked up again burning embers will not fall on the smoker's clothing, rugs, tables or the like.

A further object of this invention is to provide a structure wherein the cigarette may easily and safely be engaged with the supporting means and whereby the removal of the cigarette therefrom is facilitated so that the smoker can position the cigarette upon the supporting means without the exercise of undue care and so that accidental striking of the tray will not cause the cigarette to be thrown onto a table, floor or the like.

A still further object of this invention is to provide an improved ashtray structure having a cigarette supporting means which is adapted to hold the cigarette at an angle with the burning end lowermost so that in the event the cigarette is left on the supporting means the burning stub will fall into the tray, the supporting means also being so constructed that the cigarette will be held against accidental displacement on the support.

Another object of this invention is to provide a tray structure and cigarette supporting means which can readily be made out of metal, glass, composition material, or a combination of materials so as to present an attractive tray structure.

With the foregoing and other objects in view, the invention will be more fully described hereinafter, and will be more particularly pointed out in the claim appended hereto.

In the drawing, wherein like symbols refer to like or corresponding parts throughout the several views,

Figure 1 is a top plan view of an ashtray constructed according to an embodiment of this invention.

Figure 2 is a sectional view taken on the line 2—2 of Fig. 1.

Figure 3 is a sectional view taken on the line 3—3 of Fig. 1.

Figure 4 is a fragmentary side elevation of a modified form of cigarette support.

Figure 5 is a fragmentary side elevation of a further modified form of cigarette support.

Referring to the drawing, and first to Figs. 1 to 3, the numeral 10 designates generally a tray structure which comprises a bottom wall 11, upstanding side walls 12 and upstanding end walls 13. In the present instance the tray 10 is constructed in rectangular configuration, but it will be understood that I do not wish to be limited to the particular configuration of this tray 10, as it may be made round or any other desired configuration.

The tray 10 is designed to retain a quantity of cigarette ashes and stubs, and is also designed to support cigarettes in such a manner that the ashes from the burning cigarettes will fall directly into the tray 10. In the present instance I have provided two cigarette supporting devices 14 and 15 which are secured to the bottom wall 11 and extend upwardly thereof and above the upper edges of the side and end walls 12 and 13, respectively.

The cigarette supporting devices 14 and 15 are mounted in opposed relation on the tray 10 and are disposed adjacent the end walls 13. The support 14 comprises an upright post or standard 16 which at a point below the upper end thereof is provided with an outstanding and substantially right angularly disposed arm 17 having a cigarette rest or seat 18. The rest or seat 18 is positioned closely adjacent the post or standard 16, and the outer end of the arm 17 is preferably downwardly curved or flared as at 19, thus forming the lower portion of a throat or guide.

The post or standard 16 terminates at its upper end in an arm 20 which overlies the arm 17 and which at its free end is provided with an upwardly curved portion 21 coacting with the curved portion 19 of the arm 17 to provide a throat or guide for guiding the cigarette C between the arms 17 and 20.

The seat or rest 18 provided in the arm 17 is V-shape, but this seat or rest may be of different design, as shown in Figs. 4 and 5. In Fig. 4 the arm 17a of the post 16a is provided with a substantially T-shaped rest or seat 18a, and in Fig. 5, the arm 17b is provided with a concave rest or seat 18b.

It will also be noted in Fig. 2 that the lower

55 55

arm 17 is relatively longer than the upper arm 20 for the purpose of facilitating the placement of the cigarette C on the rest 18.

In the use of this tray structure, the cigarette C is placed on the support 14 by sliding the cigarette between the arms 17 and 20 with the cigarette substantially horizontal. The space between the two arms 17 and 20 is slightly more than the diameter of the cigarette C so that when the cigarette C is in the innermost position and engaging on the rest 18, the cigarette C may be released and the longer end thereof on one side of the support 14 will incline downwardly. One corner of the arm 20 will contact with the cigarette C and an opposite corner of the rest 18 will engage the cigarette so that the cigarette will be thereby held against downward movement, being supported in substantially the position indicated by dotted lines in Figs. 2 and 3. It is, of course, well known that cigarettes are of a construction such that they will burn to the end, and it is not uncommon with ordinary ashtrays embodying a concave rest for the stub of the cigarette to be accidentally knocked off or otherwise fall beside the tray and thus cause damage to a table or the like. With this improved support, however, if the cigarette should be left on the support 14 between the arms 17 and 20, the ashes therefrom will fall into the tray 10, and when the weight of the end of the

cigarette projecting upwardly of the support 14 is greater than the weight of the lower end, the upper end will tilt downwardly and fall into the tray 10.

It is of course understood that various changes and modifications may be made in the details of construction of the above specifically described embodiment of this invention, such changes and modifications being limited only by the scope of the claim appended hereto.

What is claimed is:

An ashtray comprising a tray structure, a standard secured to and extending upwardly of said tray structure, and a pair of horizontally disposed supporting arms carried by said standard, each of said arms having flat confronting horizontal faces and vertical faces at right angles to said horizontal faces to thereby form a relatively sharp edge on opposite sides of each arm, the space between said arms being substantially greater than the diameter of a cigarette, the lowermost of said arms having a transverse seat thereacross to receive a cigarette, the width of the arms and the spacing thereof being such as to maintain a cigarette at an inclination to the horizontal, the sharp edge of the upper arm providing a means to hold the cigarette against slipping.
